(57) **CLAIM**

The ornamental design for a reversible portable serving tray, as shown and described.

DESCRIPTION

FIG. 1 is a top perspective view of a reversible portable serving tray, showing my new design;

FIG. 2 is an exploded top perspective view thereof, illustrated with a cover detached from a base, the base in an upright orientation;

FIG. 3 is an exploded front elevational view thereof, the rear elevational view being a mirror image thereof;

FIG. 4 is an exploded left-side elevational view thereof, the right-side elevational view being a mirror image thereof;

FIG. 5 is an exploded top plan view thereof;

FIG. 6 is an exploded bottom plan view thereof; and,

FIG. 7 is a perspective view thereof.

The broken lines in the figures depict portions of the reversible portable serving tray that form no part of the claimed design.

1 Claim, 6 Drawing Sheets
